UNITED STATES PATENT OFFICE.

WHILLDIN D. HALFMANN, OF PHILADELPHIA, PENNSYLVANIA.

HAT-CONFORMING MEANS.

Specification of Letters Patent.

Patented July 11, 1916.

1,190,998.

Application filed October 7, 1915. Serial No. 54,575.

To all whom it may concern:

Be it known that I, WHILLDIN D. HALFMANN, a citizen of the United States, residing in Philadelphia, Pennsylvania, have invented certain Improvements in Hat-Conforming Means, of which the following is a specification.

My invention relates to means for enabling hats of various kinds to properly conform to the head, more particularly hats worn by men; and the object of my invention is to provide a resilient, compressible or elastic cushion between the hat crown and the head. Preferably this cushion will lie between the wall of the hat crown and the sweat band. When so employed, the sweat band will normally lie a slight distance away from the body of the hat; held out by the elastic or resilient cushion. By such an arrangement, any hat of proper size will readily and comfortably conform to the shape of the head without the necessity of altering the shape of the hat crown. These and other features of my invention are more fully described hereinafter, reference being had to the accompanying drawings, in which:

Figure 1, is a perspective view, partly in section, showing a portion of the hat crown with conforming means embodying my invention applied thereto; Fig. 2, is a sectional plan view of part of a hat and its sweat band, showing conforming means embodying my invention interposed between such sweat band and the hat crown; Fig. 3, is a sectional view on the line III—III, Fig. 2, and Figs. 4, 5, 6, 7, 8 and 9, are views showing other forms of resilient conforming means within the scope of my invention.

Hats as usually made, more particularly hats of straw, stiff felt, and silk, have a substantially standard contour usually oval. The shape of the wearer's head, however, rarely conforms to the supposed standard shape of the hat opening, and as is well known, the common practice is to attempt to shape a hat at the time of purchase to conform to or fit the head of the wearer. Such attempt at conformation, however, is rarely successful; the material of which the hat is composed preventing proper re-shaping. By placing a continuous resilient cushion between the crown of the hat and the wearer's head, preferably between the sweat band and the hat crown, however, proper provision is made for insuring that

the hat will fit the head of the wearer, since the protuberances of the head will compress the cushion member at the points desired without creating undue pressure upon the head, while the hollow portions of the skull may receive the fully expanded portions of the resilient cushion.

In the drawings, 1 represents the hat, 2 the sweat band, and 3 a continuous coil of wire which is slightly flattened and lies between the wall of the hat crown and the sweat band. This coiled wire may be held in its slightly flattened condition by various means, but must occupy such position with respect to the wall of the crown and the sweat band as to cause the latter to project inwardly a slight distance so as to insure a proper amount of compressibility between the sweat band and the hat crown when the hat is placed upon the head.

In constructing the resilient spacing and conforming cushion member constituting my invention, I prepare a continuous coil of fine wire, preferably of a non-ferrous character, and secure the same to the hat crown, preferably between the latter and the sweat band. The coils of this wire member may be round, oval or flattened. Various means of securing this coiled wire spring to the hat may be employed. For instance, I preferably dispose adjacent the same, as shown in Figs. 1, 2 and 3, a flexible continuous member 5, usually of metal, which may be readily secured to the hat crown; which member has clips or prongs 6, struck up from the body of the same, for attachment to the convolutions of the coiled spring so as to hold the latter in the proper collapsed position, and yet with sufficient resiliency to form a cushion for engagement with the head or hold the sweat band away from the hat crown in the proper position. In some instances the coiled spring may be inclosed in a fabric cover 7 to facilitate the placing of the same in position in the hat; the cover being sewn in place. In some instances the fabric cover for the coiled spring may be omitted, and the spring secured in place by fastening the member to the hat crown. The cover is shown in Figs. 1, 2 and 3, but omitted in Fig. 4, in which arrangement the member 5 is secured to the hat crown.

In the structures shown in Figs. 1, 2, 3 and 4, the member 5 is disposed externally of the spring. In Fig. 5, however, I have shown this member 5 internally arranged with re-

spect to a coiled spring; the cover 7 being also omitted. In Fig. 6, the coiled spring is shown as held in place by long and short stitches, 8 and 9, respectively, between the 5 hat crown and the sweat band. In Figs. 7, 8 and 9, I show a wire spring 3^a with flattened coils which will stand out from the hat crown as indicated. No matter how applied, however, the spring will project a slight distance inwardly from the inner wall of the hat crown to form a cushion for the head, and when between the hat crown and sweat band will support the latter in proper position so that when the hat is applied to the head portions of the spring will compress and insure that the hat conforms properly and comfortably to the head.

By preference, I connect the lower edge of the sweat band with the hat crown by a row 20 of elongated stitches or a perforated strip 10, and as the coiled wire will hold the sweat band away from the inner wall of the hat at all points where the pressure of the head is not applied, the structure I have devised affords an admirable ventilator for the hat, 25 permitting a free circulation of air to pass into the cavity of the crown substantially at all points of the head.

While I have referred to the use of a 30 spring cushion made of metal, it will be understood that a cushion might be made of a coil of stiff fiber having the desired resiliency when coiled.

I claim:

- 35 1. The combination with a hat having a sweat band, of a normally-flattened coiled member forming a cushion and disposed on the inside of the crown of the same adjacent the portion normally contacting with the head, and means independent of the sweat band for securing said coiled member to the hat crown whereby said member is maintained in its partially flattened position.
- 40 2. The combination with a hat and the sweat band thereof, of a coiled spring disposed on the inside of the crown of the hat

Copies of this patent may be obtained for five cents each, by addressing the "Commissioner of Patents, Washington, D. C."

adjacent the portion normally contacting with the head, a continuous member independent of the sweat band to which the coils of said spring are attached for holding the 50 spring in partially flattened position to provide a cushion between the head and the hat, and means for securing said spring and the continuous member to the hat.

3. The combination with a hat and the 55 usual sweat band therefor, of a coiled spring interposed between said hat and its sweat band, a continuous member independent of the sweat band and disposed within the spring to which coils of the latter are attached for holding the spring in a partially flattened condition to provide a cushion between the sweat band and the hat, and means for securing said continuous member to the hat to hold said coiled spring in place. 65

4. The combination with a hat and a sweat band therefor, of a cushioning member for the head disposed between the hat and its sweat band, said cushioning member comprising a coiled spring, a continuous 70 member independent of the sweat band and to which the coils of the spring are separately attached whereby said spring may be held in a partially flattened condition, means for holding said continuous member and 75 the spring to the hat, and an inclosing cover for said spring and its continuous connecting member.

5. The combination with a hat and a sweat band therefor, of a cushioning member 80 for the head disposed between the hat and its sweat band, said cushioning member comprising a coiled spring, and a continuous member independent of the sweat band disposed within the same, said member having prongs engaging the several coils 85 of the spring whereby said spring may be held in a partially flattened condition, and means for securing said cushioning member in place.

WHILLIDIN D. HALFMANN.
